UNITED STATES PATENT OFFICE.

JOSEPH LEDWINKA, OF PHILADELPHIA, PENNSYLVANIA, ASSIGNOR TO EDWARD G. BUDD MANUFACTURING COMPANY, OF PHILADELPHIA, PENNSYLVANIA, A CORPORATION OF PENNSYLVANIA.

CLOSED BODY STRUCTURE FOR AUTOMOBILES.

Application filed November 6, 1919. Serial No. 336,058.

This invention relates to closed body structures for automobiles.

The object of the invention is to provide a sheet steel closed body structure for automobiles which is simple in construction, which can be quickly and rapidly assembled, which is strong and durable, and efficiently braced against the stresses and strains to which such bodies are subjected in use, and which is economical to manufacture.

Other objects of the invention will appear more fully hereinafter.

Referring to the accompanying drawings,

Fig. 1 is a view in side elevation of the rear portion of a closed body structure embodying the principles of my invention.

Fig. 2 is a similar view of the front portion of the body.

Fig. 3 is a view in rear elevation of the same, parts broken out to disclose the interior arrangement.

Fig. 4 is a view in vertical central longitudinal section of the rear portion of the body on the line 4, 4, Fig. 3, looking in the direction of the arrows.

Fig. 5 is a vertical section on the line 5, 5, Fig. 3, looking in the direction of the arrows.

Figs. 6, 7 and 8 are respectively broken detail views on the lines 6, 6; 7, 7; and 8, 8; Fig. 2, showing the corner post structure for the front door at the various respective points.

Fig. 9 is a broken detail view in section of the center post on the line 9, 9, Fig. 2.

Figs. 10 and 11 are respectively broken detail views in section on the lines 10, 10; and 11, 11; Fig. 1, through the rear door post.

Fig. 12 is a view in side elevation, parts broken off, showing the cowl portion of the body.

Fig. 13 is a broken detail view in vertical section on the line 13, 13, Fig. 12 through the threshold strip and associated parts of the front door opening.

Fig. 14 is a view in vertical section through a door.

Fig. 15 is a broken detail view in section on the line 15, 15, Fig. 1.

Fig. 16 is a broken detail view in section on the line 16, 16, Fig. 1.

Fig. 17 is a broken detail view in vertical section on the line 17, 17, Fig. 1.

Fig. 18 is a sectional view similar to Fig. 16.

The same part is designated by the same reference numeral wherever it occurs throughout the several views.

In the manufacture of closed body cars difficulty has been experienced heretofore in providing an all steel body of the closed body type by reason of the stresses and strains to which such bodies are subjected in use.

Modern practice requires not only simplicity in the structure of closed bodies for cars but strength and rigidity therein as well as economy in manufacture. Where it is possible to employ sheet steel in the manufacture of closed bodies greater strength and durability are secured and a more rugged structure produced, but to enable the em-

ployment of sheet steel stampings in the manufacture of such bodies it is necessary to provide efficient means for bracing and strengthening the structure at the points where strains are imposed thereon. It is also desirable and necessary to provide a structure of the character referred to which can be quickly and easily assembled and the parts secured together so as to form one integral structure. It is among the special purposes of my present invention to provide a closed car body constructed of sheet steel stampings which are arranged and disposed in such manner as to be capable of rapid assembly, and wherein provision is made for efficiently strengthening and bracing the structure at the points desired.

Referring to the accompanying drawings I have shown a body of the closed car type consisting of the rear portion 20, Fig. 1, the front portion indicated generally at 21, Fig. 2, and the cowl portion indicated generally at 22, Fig. 12, with a doorway opening between the front and rear portions 21, 20, to receive the hinged door, and a doorway in the front portion to receive the usual hinged door therefor, the door openings in the front and rear portions of the body being separated by a central door post indicated generally at 23,

Referring to the accompanying drawings I have shown a body of the closed car type consisting of the rear portion 20, Fig. 1, the front portion indicated generally at 21, Fig. 2, and the cowl portion indicated generally at 22, Fig. 12, with a doorway opening between the front and rear portions 21, 20, to receive the hinged door, and a doorway in the front portion to receive the usual hinged door therefor, the door openings in the front and rear portions of the body being separated by a central door post indicated generally at 23,

Referring to the accompanying drawings I have shown a body of the closed car type consisting of the rear portion 20, Fig. 1, the front portion indicated generally at 21, Fig. 2, and the cowl portion indicated generally at 22, Fig. 12, with a doorway opening between the front and rear portions 21, 20, to receive the hinged door, and a doorway in the front portion to receive the usual hinged door therefor, the door openings in the front and rear portions of the body being separated by a central door post indicated generally at 23,

Referring to the accompanying drawings I have shown a body of the closed car type consisting of the rear portion 20, Fig. 1, the front portion indicated generally at 21, Fig. 2, and the cowl portion indicated generally at 22, Fig. 12, with a doorway opening between the front and rear portions 21, 20, to receive the hinged door, and a doorway in the front portion to receive the usual hinged door therefor, the door openings in the front and rear portions of the body being separated by a central door post indicated generally at 23,

Referring to the accompanying drawings I have shown a body of the closed car type consisting of the rear portion 20, Fig. 1, the front portion indicated generally at 21, Fig. 2, and the cowl portion indicated generally at 22, Fig. 12, with a doorway opening between the front and rear portions 21, 20, to receive the hinged door, and a doorway in the front portion to receive the usual hinged door therefor, the door openings in the front and rear portions of the body being separated by a central door post indicated generally at 23,

Figs. 2 and 9, the front door indicated generally at 24, Figs. 6 and 7, being hinged to a front door post indicated generally at 25, Figs. 2, 6, 7, and 8. The rear door indicated at 26, see Figs. 9 and 10, being likewise suitably hinged to and cooperating with a rear door post indicated generally at 27, Figs. 1, 10 and 11.

In constructing the tonneau or rear portion 20 of the closed body I employ sheet steel side stampings 28, 29, see Fig. 17, which are shown as separate pieces with their adjacent edges lapped upon each other as indicated at 30 and fastened together by electrically welding same or otherwise, but it is obvious that this stamping may be made in one piece and suitably pressed out into the shape and contour to be given to the tonneau. The portions 28, 29, are offset from each other on their lateral side portions to form the recess 31 constituting the usual wheel house. The lower part of the portion 28 of the tonneau panel is likewise offset inwardly as indicated at 32 to form a shoulder 33 upon which rests the seat panel 34. The extreme lower edge of the tonneau panel 28 is formed with a flange 35 which fits to and is electrically welded or otherwise secured to the longitudinally extending sill member 36. The sill member 36 likewise forms a support for the flooring panel 37. The side edges of the seat panel 34 rest upon the shoulders 33. The rear edge of the seat panel 34 rests upon an angle plate 38, see Fig. 4, suitably secured to a reinforcing member 39 which is vertically disposed on the interior surface of the tonneau panel. The front edge of the seat panel is supported upon a shoulder 40 formed on a transversely extending vertically disposed panel 41 suitably secured to an upturned flange 42 on the floor panel 37. The upper edge of the heel board or plate 41 is upturned as indicated at 43, see Fig. 4, to form a retaining edge for the seat cushion when supported upon the seat.

The upper part of the tonneau is formed with a window opening indicated at 44, Figs. 1 and 5, in which is disposed a window 45. The window pane in this structure is received at its upper, lower and side edges in grooves or channels formed in the angle pieces or stampings 46 suitably positioned upon window frame members 47. These stampings are formed with flanges 48 which fit over inturned flanges 49 of the stampings 50 which form the upper walls of the tonneau of the enclosed body, and which likewise form the roof panel. The stampings 46 are formed with central channels which are pressed therein to receive the pane edges of the window and these channels fit into rabbets formed in the frame members 47, thus forming a very simple and substantial window structure. The panel 50 at its

lower edge is formed with an inturned flange 51 which fits against a corresponding flange 52 formed at the upper edge of the body panel or portion 29. In order to suitably reinforce the connection of these two flanges 51 and 52 and to strengthen the joint between them a reinforcing member or bar 53 is applied to these flanges, and the flanges and reinforcing bar 53 are secured together by riveting, welding, or otherwise. This structure provides a very efficient rigid structure for connecting the upper and lower portions of the body panels and permits me to employ a thinner sheet for the panel 50 than is employed for the panel portion 28 or 29.

Sometimes and ordinarily the roof portion of the panel 50 may be made in separate sections 50, 54, secured together by overlapping flanges 55, 56, offset from the planes of the bodies of said panels as shown in Fig. 5 and suitably secured together. This arrangement makes a channel formation in the roof and upper side portions of the panels which add strength and rigidity to this structure. The channels thus formed also afford means for supporting an interior channel member 57 to which the interior trim and upholstery may be attached. This channel member 57 is suspended in the upper portion of the tonneau by means of angles or straps 58 which are secured to the channel formed by the flanges 55, 56, by means of blocks 59 placed in the channel and riveted or otherwise connected through the flanges 55, 56 to the upper ends of the angles 58. The lower ends of the angles 58 fit in and are suitably secured to the channel member 57. In order to prevent unnecessary rattle and squeaking the channel member 57 is suspended from the roof of the tonneau and is carried out of contact with the side walls of the tonneau body, a space being left between the channel member 57 and said side wall, as indicated at 60.

Along its side edges the roof panel 50, above the window opening 44 and the door openings, is formed with an outwardly extending flange 61 which is fitted in and secured to a channel stamping 62 which thus forms a water trough to prevent the dripping from the roof from falling over the window or the door, and attached to the interior flange of the channel stamping 62 is another channel stamping 63 which may carry a wooden or other block or bar 64 for convenience in attaching the interior trim. The side doors 26 of the tonneau, and likewise the front doors 24 may be of the usual or any suitable or convenient structure formed of pressed steel panels, and shaped to conform to the vertical contour and outline of the body and formed with flanges 66 at their vertical and bottom edges to abut against suitable shoulders formed in the

door posts to which said doors are hinged and the central door post disposed between the adjacent edges of the front and rear doors and the door sill and threshold structure, respectively. These doors, if desired, and as usual, carry glass windows 65 in their upper portions, the construction of which windows may, if desired, follow the construction and mounting of the window 45 above described. The rear door 26 is hinged to a door post formed along the vertical edge of the rear or tonneau portion of the body and indicated generally by reference numeral 27, Figs. 1 and 11. This post consists of stampings 67, 68 and 69, the latter being of substantially U-shape in cross section, to the outer surface of one flange of which the stamping 67 is applied, and to the outer surface of the other flange of which the stamping 68 is applied, these stampings 67 and 68 being shaped to the desired form and configuration and suitably secured together and to the stamping 69 by welding or otherwise. A cap stamping 70 is applied to one vertical side of the post and is made removable, being retained in place by removable bolts 71, and this cover plate stamping is formed with a flange portion 72 which cooperates with an offset portion 73, see Figs. 10 and 11, to form a channel way to receive the window 45 or the frame thereof. By making the cap 70 removable the insertion and removal of the window is facilitated.

On the portion of the post 27 opposite that of the location of the window 45 the post stamping member 67 is formed with a shoulder 74 to form an abutment for the vertical flange 66 along the vertical rear edge of the door 26 and at its inner portion the member 67 is formed with a flange 75 to receive the portion 76 of the edge of the door. Thus this portion of the post stamping 67 is what may be termed a double Z section taking into account the front wall and the shoulder 74. In the lower portion of the post, below window 45, stamping 67 has a simple Z section, shown clearly in Figure 10, and in this case flange 66 of the door is accommodated in the angle formed between the outer arm of the Z and the inturned flange of the paneling 29.

The central post 23 between the front and rear doorways is formed of a stamping 77 suitably pressed into shape to form the shoulders 78, 79, 80 and 81 to receive respectively the vertical edge flanges 66 and portions 82, 83, of the front and rear doors 24, 26 respectively. To this end the stamping 77 is formed into generally channel formation. The inner open edge of the channel into which the stamping 77 is formed is closed by a removable cover member 84 which is connected by removable bolts 85 to struts or spiders 86 secured within the channel member 77. This cover plate stamp-

ing 84 conceals the interior structure of a channel post and forms a neat finish therefor. The cover plate 84 is formed with edge flanges 87 which fit within and are secured to the inner surfaces of the edge portions 70 of the channel post 77, the plates 84 being extended beyond the edges of the channel post 77, all as clearly shown in Fig. 9.

The front door 24 is hinged to a door post indicated generally at 25, Figs. 2, 6, 7 and 8. At the points above the cowl 22 the front door post 25 is formed of a stamping 88 which is pressed into channel formation with a shoulder 89 to receive the adjacent edge flange 66 of the door 24. Upon this channel post are mounted the standards 89' which support the front or windshield flange 90 in which the window 91 is mounted. Lower down on this post the cowl panel 22 is attached as shown in Figs. 7 and 8.

At the doorways I provide a door sill and threshold structure which is also simple and easily assembled and wherein the parts are so connected as to efficiently brace each other. I have shown such an arrangement in Figs. 12 and 13 wherein a stamping 92 is secured to the frame sill 36 and is pressed upwardly as at 93 to conform to the vertical curvature of the body. At its upper outer edge the stamping 92 is bent inwardly to form a shoulder as at 94 to form an abutment for the edge flange 66 at the bottom edge of the door. Engaging over the laterally extending flange 95 above the shoulder 94 of stamping 92 is a channel shaped stamping 96 which forms a finish and a reinforcing strip at the threshold of the door. Over this channel member 96 is the threshold strip proper 97 which completes the finish of the parts. The channel 96 is formed at its inner edge with a flange 98 upon which rests the floor board 99.

The various stampings and elements may be stamped out in quantities and in standard sizes and shapes and may be assembled and secured together in proper relation quickly and easily, thus greatly reducing the time required to assemble and complete bodies of the character set forth, and when assembled and united as above described they contribute to the production of a strong, rugged body structure in which the various members reinforce and brace each other. The invention disclosed herein is claimed broadly in my pending application for Letters Patent for improvements in automobile bodies, Serial No. 504,927, filed October 3, 1921, to which cross-reference is hereby made. The issuance of this patent is not to be construed as an abandonment of the subject-matter disclosed but not claimed herein, as such subject-matter is claimed in said pending application.

Having now set forth the objects and nature of my invention, and a construction embodying the features and principles there-

of, what I claim as new and useful and of my own invention and desire to secure by Letters Patent, is,—

1. In a sheet metal closed body structure for automobiles, sheet steel stampings forming the sides and roof of the body, a trim engaging member, and means to suspend said member from the roof of the body.
2. In a sheet metal closed body structure for automobiles, sheet steel stampings forming the sides and roof of the body, a trim engaging member, hangers to carry and support said member out of contact with the walls of the body, said hangers being suspended from the body roof.
3. In a sheet metal closed body structure for automobiles, sheet steel stampings forming the sides and roof of the body, a channel member arranged inside the body near the top thereof, and means to suspend said member from the body roof.
4. In a sheet metal closed body structure for automobiles, sheet steel stampings forming the sides and roof of the body, said stampings having off-set engaging flanges at their meeting edges, forming a depression, a filler strip seated in said depression, a channel member disposed inside the body and suspending hangers for said member, said hangers being supported from said strip.

In testimony whereof I have hereunto set my hand on this 23rd day of October A. D., 1919.

JOSEPH LEDWINKA.
